GOLF PUTTING DEVICE

Joseph Niamtu, Jr., 1426 26th St. NW., Canton, Ohio

Filed Apr. 19, 1963, Ser. No. 74,522

Term of patent 14 years

(Cl. D34—5)

FIG. 1 is a perspective view of a golf putting device in the open position, showing my new design;

FIG. 2 is a front elevational view thereof;

FIG. 3 is a top plan view of the device in the closed position with a golf ball shown in broken lines for illustrative purposes only;

FIG. 4 is a front elevational view of the device in a closed position;

FIG. 5 is a side elevational view thereof; and

FIG. 6 is a rear elevational view thereof.

The flag has been omitted from FIGS. 2 through 6 for convenience of illustration.

I claim:

The ornamental design for a golf putting device, substantially as shown and described.
